UNITED STATES PATENT OFFICE.

CHARLES E. REYNOLDS, OF WOODSON, AND WILLIAM E. REYNOLDS, OF MODESTO, ILLINOIS.

ROTARY ENGINE.

SPECIFICATION forming part of Letters Patent No. 734,430, dated July 21, 1903.

Application filed May 20, 1903. Serial No. 158,016. (No model.)

To all whom it may concern:

Be it known that we, CHARLES E. REYNOLDS, residing at Woodson, in the county of Morgan, and WILLIAM E. REYNOLDS, a resident of Modesto, county of Macoupin, State of Illinois, citizens of the United States, have invented certain new and useful Improvements in Rotary Engines, of which the following is a specification.

10 This invention relates to improvements in rotary engines wherein a gate in the cylinder is operated in conjunction with a valve, the latter being operated by a separate and distinct mechanism.

15 The object of the invention is to provide a gate and valve operating mechanism timed to coact with each other and each being yieldingly operated by a hand-lever which is locked in a predetermined position.

20 In carrying out our invention we propose arranging the gate and valve in a manner which will permit the steam to expand between the piston-blade and the gate irrespective of the travel of the engine. We have 25 therefore devised a reversible expansion rotary engine of simple construction and one which, owing to the small number of parts, is easily and conveniently operated.

Other objects and advantages will be hereinafter referred to in this specification and be particularly pointed out in the claims.

In the drawings, Figure 1 is a perspective view of our improved rotary engine. Fig. 2 is a similar view looking from the other side. 35 Fig. 3 is a transverse section on the line X X. Fig. 4 is a longitudinal section on the line Y Y. Fig. 5 is an enlarged detail perspective view of the valve shaft and gate. Fig. 6 is a diagrammatic view of the disk which operates the valve. Figs. 7 and 7^a are diagrammatic views illustrating the position of the parts when the steam is cut off. Figs. 8 and 8^a are similar views, but showing the position of the parts when the piston is traveling toward the right. Figs. 9 and 9^a are similar views, but showing the position of the parts when the piston is traveling toward the left.

The same numerals refer to like parts in all the figures.

50 1 represents a cylinder provided with heads 2 and 2^a, mounted on a base 3. A shaft 4

passes through the cylinder and bears a piston 5, having a blade 6, the latter bearing against the inner surface of the cylinder 1. The shaft 4 is supported in bearings 7 and 55 carries a fly-wheel 8 and two disks 9 and 10.

11 represents a steam-chest, 12 a steam-supply pipe communicating therewith, and 13 and 14 are inlet-ports which communicate with the steam-chest and the cylinder 1. A 60 shaft 15 is mounted in the head 2^a and a bearing on the steam-chest. A disk valve 18 is fixed to the shaft 15 and fits tightly against the face of the head 2^a, and it is provided with port 19, designed to form communication with 65 the steam-chest and cylinder through the medium of either of the ports 13 and 14. On the outer end of the shaft 15 is secured a hub 21, having two levers 21^a and 21^b, one of which is always in the path of a cam 22 on the periphery of the disk 9. As shown in the diagram illustrated in Fig. 6, it will be seen that by adjusting the cam of the disk 9 the lever 21^a and 21^b may be timed to introduce steam 70 into the cylinder at any period or at any part 75 of the revolution of the piston.

23 represents an arm rigidly mounted on the shaft 15, and 24 is an operating-lever, which is loosely mounted on the said shaft 15. A spring 25 connects the arm 23 and lever 24. 80 A segmental rack 26, having suitable notches 27, is fastened to the engine, and the lever 24 has a lug which engages the notches 27, and thus locks the parts to set the valve to introduce steam to run the engine backward or 85 forward, as will be hereinafter described.

30 is a second shaft mounted in the head 2 and socket in the valve 18, and it is hollow at its outer end, as shown at 31, and adjacent the hollow portion it has formed on it a gate 90 32. The gate is segmental, its inner face conforming to the curve of the cylinder 1, while its outer periphery is struck from the center of the shaft 30. The gate works in a seat 34 in the cylinder and is adapted to form an 95 abutment, against which the steam acts when introduced to the cylinder. The inner face of the gate conforming to that of the cylinder, obviously when the gate is opened its seat is closed and the contour of the cylinder is not 100 interrupted.

A bifurcated projection forming two lugs

36 and 37 is rigidly fixed to the end of the shaft 30, one or the other of the lugs being in the path of and adapted to be struck by a lug 39 on the disk 10, the one being struck depending, of course, on the direction of the travel of the piston, as will be hereinafter explained. An arm 39^a is fixed to the shaft 30, and also mounted loosely on said shaft is an operating-lever 40, the arm 39^a and lever 40 being connected by a spring 41, a segmental rack being employed to lock the lever in a fixed position. These parts are duplicates of those described in connection with the valve 18.

15 The parts thus described, the operation is as follows, attention being particularly directed to the diagrams illustrated in Figs. 7, 7^a to 9, 9^a: Assume the shaft to be in the position illustrated in Fig. 7, showing that no steam can be admitted into the cylinder 1, the location of the valve and the ports being illustrated in Fig. 7^a. If the engine is to be run toward the left looking at Fig. 1, the operating-levers 24 and 40 will be thrown in the same direction, which, through the medium of their springs and arms, rocks the shafts 15 and 30, hence the valve 18 and gate 32, as shown in Figs. 8 and 8^a. Steam now passes from the chest 11 through the ports 19 and 13 and is expanded between the gate and the piston-blade, which revolves the piston in the direction of the arrow A. The projection on the disk 10 will therefore strike one of the legs 36 37 once in each revolution or just prior to the time the blade 6 reaches the gate 32, thus raising the latter and permitting said blade to pass. Immediately the blade passes the gate the spring 41 acts to again close it, at which time one of the levers 21^a 21^b is struck by the cam on the disk 9, and steam is admitted to the cylinder 1 until the termination of the cam is reached. The exhaust steam is carried off through the hollow portion 31 of the shaft 30. To reverse the engine, Figs. 9, 9^a, the levers 24 and 40 are thrown toward the right, whereupon the lever 21^a and leg 31 are brought into alignment with their respective lug and cam, and the position of the valve 18 is relatively positioned with the port 13, whereupon the steam enters said port through the port 19, and hence the direction of the engine is reversed.

The resilient connection between the operating-levers of the gate and the valve is such that while the springs are strong enough to cause the arms to move with the levers to change the position of the parts nevertheless there will be resiliency sufficient to permit the joints to break when the cams strike the various trips. This feature of our invention we regard as of vital importance.

What we claim as new is—

1. In a rotary engine, the combination with a cylinder, of a piston, a gate mounted in the cylinder and adapted to form either a steam-abutment or a part of the cylinder, a gate-shaft, an arm rigid with the shaft, an oper-

ating-lever loosely mounted on the shaft, a resilient connection between the arm and the lever, means connected to the piston for operating the gate, a steam-chest, and means coacting with the gate for introducing steam to the cylinder, substantially as described.

2. In a rotary engine, the combination with a cylinder, of a piston, a gate mounted in the cylinder and adapted to form either a steam-abutment or a part of the cylinder, a gate-shaft, an arm rigid with the shaft, an operating-lever loosely mounted on the shaft, a resilient connection between the arm and the lever, means connected to the piston for operating the gate, a steam-chest, a valve therein having a port, two ports formed in the cylinder, a valve-shaft, an arm rigid with the shaft, an operating-lever loosely mounted on the shaft, means resiliently connecting the lever and the arm, and means controlled by the piston for actuating the valve, substantially as described.

3. The combination with a cylinder, a piston bearing a blade, a valve-chest, an oscillating valve having an opening, a valve-shaft bearing levers at or near one end, a cam adapted to strike one of said levers, two ports in the cylinder behind the valve, mechanism for bringing the opening in the valve into register with either of said ports, a gate, a gate-shaft mounted in line with the valve-shaft, mechanism for actuating the gate, and mechanisms for changing the operating relation of the gate with that of the valve to determine the direction of the travel of the piston, substantially as described.

4. The combination with a cylinder, a piston bearing a blade, a valve-chest, an oscillating valve having an opening, a valve-shaft bearing levers at or near one end, a cam adapted to strike one of said levers, two ports in the cylinder behind the valve, mechanism for bringing the opening in the valve into register with either of said ports, a gate, a hollow gate-shaft which communicates with the cylinder and the atmosphere, mechanism for actuating the gate, an operating-lever, and a resilient connection between the lever and the hollow shaft, substantially as described.

5. The combination with a cylinder, a piston bearing a blade, a gate mounted in the cylinder and adapted to form either a steam-abutment or a part of the cylinder, a gate-shaft projecting from the ends of the gate below the center thereof, a portion of the shaft being hollow and communicating with the cylinder and the atmosphere to form an exhaust-pipe, mechanism controlled by the piston for actuating the gate in either of two predetermined directions, a valve having an opening therein, two ports formed in the cylinder either of which is adapted to be brought into register with the opening in the valve, and mechanism controlled by the piston for actuating the valve in either one or two directions, substantially as described.

6. In a rotary engine, the combination with a cylinder, a piston bearing a gate having a shaft, a loosely-mounted handle, a resilient connection between the handle and a projection on the shaft, mechanism for actuating the gate against the tension of the resilient connection, a valve having a stem, a loosely-mounted handle, a resilient connection between said handle and a projection on the stem, and mechanism for actuating the valve against the tension of the resilient connection, substantially as described.

7. In a rotary engine, the combination with a cylinder, a piston bearing a gate having a shaft, one portion of which is hollow and communicates with the cylinder and the atmosphere to form an exhaust-pipe, mechanism for controlling the movement of the gate, a valve in line with the shaft of the gate, an opening formed in the valve, an opening formed in the wall of the cylinder each side of the gate, and mechanism for controlling the movement of the valve, substantially as described.

8. In a rotary engine, the combination with a cylinder, a piston bearing a blade, a gate having a shaft which is hollow to form an exhaust-pipe, a loosely-mounted handle, a projection on said shaft, a resilient connection between the projection and handle, arms fast on the shaft, a cam actuated by the piston to operate against the arms, a valve-chest, a disk valve having an opening, a shaft, an opening in the cylinder each side of the gate, a loosely-mounted handle, a projection on the shaft of the valve, resilient connection between the projection and handle, arms fast on the valve-shaft, and a cam actuated by the piston to operate against the arms, substantially as described.

In testimony whereof we have signed our names to this specification in presence of two witnesses.
